[57] ABSTRACT

An electroluminescent plate is arranged closely adjacent to the projection lens of an enlarger and has a central aperture for passage through it of the light beam from the lens. A diffusing lens is disposed between the electroluminescent plate and the copy table, and a reflecting sheet having a reflecting surface disposed toward the electroluminescent plate partially covers the diffusing lens. The plates and reflector may be combined in a unitary assembly. A regulator is interposed between the electroluminescent plate and a source of power to control the intensity of the light emitted from it.

AUXILIARY LIGHTING DEVICE FOR ENLARGERS

BACKGROUND OF THE INVENTION

The invention relates to an auxiliary lighting arrangement for enlargers, wherein the light source consists of an electroluminescent plate.

There are some enlargers known wherein luminescent plates, controllable in their intensity, are used for the purposes of auxiliary lighting. These plates are mounted on a movable arm and during their use for auxiliary illumination are swung over the projection surface on which the copy material is situated. In a known apparatus, this swiveling procedure is usually 15 accomplished by a motor.

These known devices have the disadvantage, however, that it is not possible to simultaneously expose the copy material with the principal source of light and the auxiliary light source because the electroluminescent plate is interposed in and therefore necessarily interrupts the beam from the principal light source. This unduly prolongs the total exposure time.

Should the copying process be automated, a relatively expensive motorized control of the swingable plate is required, which considerably increases the cost of such an apparatus. A further disadvantage of these auxiliary lighting devices is that the electroluminescent plates, because of differences in the coating thickness caused by finishing variations, do not reflect light of the same intensity over the entire surface and consequently do not uniformly illuminate the copy material.

SUMMARY

An object of the invention is to provide an auxiliary lighting device for enlargers, wherein the aforementioned disadvantages described are avoided and which permits, together with highly uniform illumination of the copy surface, the provision of the auxiliary illumination at the same time as the principal illumination. This object is solved by an auxiliary lighting device, which is characterized in that an electroluminescent plate is arranged in the direct proximity of the enlarger lens and has a central aperture for the passage through it of the light beam coming from the lens.

In an advantageous embodiment, a diffusing lens is provided between the electroluminescent plate and the copy plane, which equalizes the irregularities in the intensity of the radiated light.

In a further development of the invention, for a further improvement of the uniformity of the radiated light, there is provided on the surface of the diffusing lens facing the copy plane a reflecting (metal) sheet partially covering the diffusing lens, whose reflecting surface is directed toward the electroluminescent plate.

It has been further shown as advantageous to incorporate the electroluminescent plate, the diffusing lens and the reflecting plate within a compact structural unit.

In addition, a regulating device is provided for the continuous adjustment of the light intensity of the light radiated from the electroluminescent plate to the various illumination ratios and enlarging factors.

BRIEF DESCRIPTION OF THE DRAWINGS

Novel features and advantages of the present invention

will become apparent to one skilled in the art from a reading of the following description in conjunction with the accompanying drawings wherein similar reference characters refer to similar parts and in which:

5 FIG. 1 is a schematic diagram in elevation of an enlarger with the novel auxiliary illuminating device which is one embodiment of this invention; and

10 FIG. 2 is an enlarged cross-sectional view of the auxiliary lighting device shown in FIG. 1 incorporated within a structural unit.

DESCRIPTION OF THE PREFERRED EMBODIMENT

The enlarger A contains a projection head 1, which accommodates a light source 2 as well as the original 3 to be projected. On the underside of the projection head 1, there is situated at least one lens 4, in whose proximity color filters 5 may be inserted into the projection beam 10.

15 The light radiated from light source 2 penetrates original 3 to be projected, color filters 5, lens 4, a screen 6 and falls onto exposable layer 7 on carrier material 8, which lies on table 9 of the enlarger. The principal illumination of the light-sensitive layer 7 occurs by the illumination of light beam 10 radiating from light source 2.

20 In order to be able to carry out an auxiliary illumination of the light-sensitive layer 7 for special assignments, there is provided in the proximity of lens 4 an auxiliary lighting device B.

25 As shown by FIG. 2, this auxiliary lighting device B consists of an electroluminescent plate 11 to which is arranged parallel and at a certain distance a diffusing lens 12, at the underside of which is mounted a reflecting plate 13 whose reflecting surface 13a is directed toward the underside of the electroluminescent plate 11. Diffusing lens 12 is partially covered by reflecting plate 13.

30 The International Dictionary of Physics and Electronics, Second Edition, D. Van Nostrand Company, Inc. Copyright 1956, 1961 defines "electroluminescence" on page 391 as follows:

35 "The conversion of electrical energy in a semiconductor directly into light. This may result either from the recombination of an electron and a hole, or from the electron impact excitation of an activator atom." Electroluminescent plate 11 provides electroluminescence.

40 Electroluminescent plate 11, diffusing lens 12 as well as reflecting plate 13 have a central cutout in order to form a passageway for the light beam 10 coming from the lens.

45 To form a compact structural unit, the individual structural parts of the auxiliary illuminating device B are connected together by suitable clamps or frame 15 as shown in FIG. 2.

50 The intensity of the light radiated from the electroluminescent plate 11 may be continuously regulated by a suitable regulating device 16 more detailed illustration of which is dispensed with, because their manner of functioning is sufficiently known. Regulating device 16 is interposed between luminescent plate 11 and a suitable power source 17 also known to those skilled in the art.

55 I claim:

60 1. An auxiliary lighting device for an enlarger having a lens which projects an image on photosensitive mate-

rial comprising an annular electroluminescent plate disposed in the immediate proximity of the lens, the annular electroluminescent plate having a central aperture to permit the light coming from the lens to pass through it, and the annular electroluminescent plate having means associated therewith for uniformly exposing the photosensitive material to its illumination.

2. An auxiliary lighting device as set forth in claim 1, characterized in that the last-named means is provided between the electroluminescent plate and the photosensitive material to be illuminated and comprises an annular diffusing lens which also has a central aperture to permit the light coming from the lens to pass through it.

3. An auxiliary lighting device as set forth in claim 2, characterized in that on the surface of the diffusing lens

facing the photosensitive material to be illuminated, there is arranged an annular reflecting plate having an area which is a portion of that of the luminescent plate the annular reflecting plate having an annular reflecting surface, and the reflecting surface being directed toward the electroluminescent plate.

4. An auxiliary lighting device as set forth in claim 3, characterized in that the annular electroluminescent and reflecting plates and the annular diffusion lens are disposed in a compact unit assembly.

5. An auxiliary lighting device as set forth in claim 1, characterized in that a regulating device is connected to the annular electroluminescent plate by means of which the intensity of the light radiated from the annular electroluminescent plate may be regulated.
